United States Patent Office

Des. 182,015
Patented Feb. 4, 1958

182,015

VENDING MACHINE

Anthony M. Caruso, New Bedford, Mass.

Application October 5, 1956, Serial No. 43,245

Term of patent 14 years

(Cl. D52—3)

Fig. 1.

Fig. 2.

Fig. 1 is a perspective view of a vending machine, showing my new design, and disclosing the right-hand side thereof; and

Fig. 2 is an elevational view of the vending machine as viewed from the left side of Fig. 1.

The dominant features of the design reside in the portions shown in full lines.

I claim:

The ornamental design for a vending machine, substantially as shown and described.
